W. S. MAYER,
INSULATOR SUPPORT,
APPLICATION FILED APR. 21, 1917.

1,271,596.

Patented July 9, 1918.

Inventor:
Walter S. Mayer,
By Charles N. Butler
Attorney.

UNITED STATES PATENT OFFICE.

WALTER S. MAYER, OF PHILADELPHIA, PENNSYLVANIA, ASSIGNOR TO ELECTRIC SERVICE SUPPLIES COMPANY, OF PHILADELPHIA, PENNSYLVANIA, A CORPORATION OF PENNSYLVANIA.

INSULATOR-SUPPORT.

1,271,596.

Specification of Letters Patent.

Patented July 9, 1918.

Application filed April 21, 1917. Serial No. 163,557.

To all whom it may concern:

Be it known that I, WALTER S. MAYER, a citizen of the United States, residing in the city of Philadelphia, county of Philadelphia, and State of Pennsylvania, have invented certain Improvements in Insulator Supports, of which the following is a specification.

My invention is a simple, inexpensive and 10 readily adjustable device for holding an insulator securely in any desired position, and it is characterized by its means for clamping it firmly to carrying means, such as a metal shape, and clamping the insulator firmly in various angular positions, permitting 15 a universal adjustment of the insulator.

The characteristic features of the invention are fully disclosed in the following description and the accompanying drawings 20 in illustration thereof.

In the drawings, Figure 1 is a front elevation of a form of my improved device fixed to a leg of an angle iron; Fig. 2 is a side elevation of the same device with the 25 angle iron shown in section; Fig. 3 is a sectional view taken on the line 3—3 of Fig. 1; Fig. 4 is a plan view of the detached device; and Fig. 5 is a front elevation of a modified construction.

As illustrated in the drawings, my improved device comprises a hollow body or barrel 1 having the jaws 1^a and 1^b extending laterally therefrom and containing the slot 1^c between the curved bearings 1^d disposed oppositely to the jaws; the jaw 1^a being serrated on its inner surface, the jaw 1^b containing the set screw 2 or the wedge 3, and the bearings 1^d being externally serrated.

This device is adapted to be fixed to the 40 shape 4 by placing the jaws 1^a and 1^b on opposite sides of a leg thereof and drawing up the screw 2 or the wedge 3 firmly against the leg.

The insulator 5 is connected to the body 1 45 by a bolt 6 which passes through the axis of the insulator, a shoe 7, the slot 1^c and a nut 8, the shoe, against which the insulator bears, having a serrated curved bearing adapted for engaging the serrations of 50 the bearings 1^d and the nut being movable in and prevented from turning by the angular ways 1^e within the barrel on opposite sides of the slot 1^c.

The bolt 6 has a screw head 6^a, countersunk in the insulator, and is adapted to be turned by a screw driver to free the engagements of the parts 7 and 8 with the exterior and interior surfaces of the bearings 1^d, when the parts 5, 6, 7, and 8 can be adjusted together to the various relatively angular positions between the limits of the slot 1^c and set securely in the desired position by screwing in the bolt.

Having described my invention, I claim: 65

An insulator and a support therefor comprising a body provided with jaws for fixing it to carrying means, bearings separated by a slot and guide ways within said bearings, in combination with a nut movable 70 within and controlled by said ways, a shoe supporting said insulator and engaging said bearings, and a bolt passing through said insulator, shoe and slot into engagement with said nut.

In testimony whereof I have hereunto set my name this 13 day of April, 1917.

WALTER S. MAYER.
